(57) **CLAIM**

The ornamental design for a feminine hygiene article, as shown and described.

DESCRIPTION

The file of this patent contains at least one drawing executed in color. Copies of this patent with color drawings will be provided by the Office upon request and payment of the necessary fee.

FIG. 1 is a front perspective view of a feminine hygiene article showing our new design;

FIG. 2 is a front view thereof;

FIG. 3 is a back view thereof;

FIG. 4 is a left-side view thereof;

FIG. 5 is a right-side view thereof;

FIG. 6 is a top view thereof; and,

FIG. 7 is a bottom view thereof.

The outermost peripheral broken line portions of FIGS. 1-7 show unclaimed subject matter only and form no part of the claimed design.

The broken lines that appear within the bounds of the claimed article of FIGS. 1 and 2 depict a portion of the pattern and form a part of the claimed design.
